CLAIM

The ornamental design for a cup lid, as shown and described.

DESCRIPTION

FIG. 1 is a perspective view of a new design for a cup lid; FIG. 2 is a top plan view thereof; FIG. 3 is a bottom plan view thereof; FIG. 4 is a front view thereof; FIG. 5 is a back view thereof; FIG. 6 is a left side view thereof; FIG. 7 is a right side view thereof; and, FIG. 8 is a perspective view thereof illustrating the cup lid in a position of use attached to a cup drawn in broken lines. The broken lines in FIG. 8 depict environment that forms no part of the claimed design.
